UNITED STATES PATENT OFFICE

GEORGE H. STEPHENS, OF NORTHBROOK, ILLINOIS, ASSIGNOR TO THE HAMMOND CLOCK COMPANY, OF CHICAGO, ILLINOIS, A CORPORATION OF DELAWARE

DESIGN FOR A CLOCK DIAL

Application filed June 29, 1931. Serial No. 40,361. Term of patent 14 years.

To all whom it may concern:

Be it known that I, GEORGE H. STEPHENS, a citizen of the United States, residing at Northbrook, in the county of Cook and State of Illinois, have invented a new, original, and ornamental Design for Clock Dial, of which the following is a specification, reference being had to the accompanying drawing forming a part thereof.

The figure is a plan view of a clock dial, showing my new design.

I claim:

The ornamental design for a clock dial, as shown.

In witness whereof, I hereunto subscribe my name this 25th day of June, 1931.

GEORGE H. STEPHENS.
